MOP STRUCTURE

Frederic E. Oakhill, Wilmette, Ill., assignor to
O-Cedar Corp'n, Chicago, Ill., a corporation of
Illinois

Application December 6, 1946, Serial No. 714,547

2 Claims. (CL 306—19)

2

This invention relates to mop structure.

In the operation of dust mops and other types of mops, difficulty is presented in applying the mop to corners and other crevices because the mop head swings loosely upon the end of the mop handle. The pivotal connection between the handle and mop head, desired for the purpose of giving effective mopping strokes along the floor, prevents the mop from being projected forwardly into corners and other difficult surfaces and the desired accurate results are thus not obtained.

An object of the invention is to provide a mop which overcomes the above disadvantages while at the same time enabling the mop handle to swing readily with respect to the mop head. Yet another object is to provide a mop structure wherein the mop head is held in a desired yielding relation to the handle, permitting the head to be projected accurately at any desired point while at the same time enabling the head to swing relatively to the handle as the head is moved along the floor surfaces. Yet another object is to provide a mop structure having a head which may be manipulated manually upon a pivot carried by the handle and wherein the handle is urged toward a predetermined position with respect to the head. Other specific objects and advantages will appear as the specification proceeds.

The invention is illustrated, in preferred embodiments, by the accompanying drawings, in which—

Figure 1 is a perspective view of a mop structure embodying my invention; Fig. 2, a longitudinal sectional view, the handle staff having been removed; Fig. 3, a detail sectional view, the section being taken as indicated at line 3—3 of Fig. 2; Fig. 4, a detail sectional view, the section being taken as indicated at line 4—4 of Fig. 2; Fig. 5, a transverse detail sectional view, the section being taken as indicated at line 5—5 of Fig. 2.

In the illustration given in Figs. 1 to 5 inclusive, 10 designates a mop head frame formed of metal, generally heart-shape in contour and with a rear portion bent inwardly and forwardly to form a handle attachment portion 11.

A handle fitting 12 is provided with a screw-threaded socket portion 13 adapted to receive the end of the handle member 14. The lower end is brought together to form a flattened portion 15 received between the handle attachment loop members 11 and pivotally secured thereto by rivet 16, as shown more clearly in Fig. 4.

The fabric mop head body 17 is looped about

the frame 10 and, if desired, may be stitched to a binding 18. A mop head plate 19 lies within the area on the interior of frame 10 and locks the mop head body 17 about the frame 10. The plate 19 is provided with a raised central portion 20 extending about the frame portion 11 and locked thereto by indentations 21 which enter aligned openings 22 in the frame portion 11, as shown more clearly in Fig. 3.

10 A bolt 23 extends through the forward portion of the raised plate section 20 and the frame portion 11, as shown best in Fig. 5. The extended portions of bolt 23 are employed on either side to support coils of a spring 24. The spring 24 on each side has a forwardly-extending portion 25 engaging the bottom of plate 19. The spring, after being looped about each end of the bolt 23, has a U-shaped portion 26 extending rearwardly and engaging the handle-receiving attachment 12. Preferably, the upper end of the U-shaped portion 26 is provided with a curved saddle 27 resting upon the tubular portion of the member 12.

25 The spring 24 may be formed of steel or any other suitable material, and is preferably of such strength as to cause the mop head to assume the aligned position shown in Fig. 1, when the mop head is lifted. The spring, however, flexes readily when the mop head is brought downwardly upon the floor, as illustrated in Fig. 2.

Operation

In the operation of the structure shown in Figs. 1 to 5 inclusive, the mop head may be raised from the floor and, under the influence of spring 24, the head assumes the position shown in Fig. 1, with the head in substantial alignment with the handle 14. The spring not only maintains the position described, but also serves to lock the head against tilting and maintains it accurately upon the end of the handle. It may thus be projected into a corner or into any narrow surface and brought downwardly upon the floor in the selected position. The handle may then be swung rearwardly, with the spring flexing, as shown in Fig. 2. In the latter position, the spring tends to urge the mop head firmly against the floor at its forward side and an effective cleaning of the corner or other difficult area is accomplished. When the mop head is raised during the cleaning operation, instead of having the head tilt at awkward angles upon the handle, the spring brings it always to the same position and enables the mop to be handled as though there were no pivotal connection between the handle

and the mop head. However, when the mop head strikes the floor again, the pivot between the head and handle becomes again effective and permits the normal mopping strokes with the mop head parallel with the floor. In addition, the action of the spring, while yielding freely against the handle, results in a desirable application of pressure upon the mop head lying upon the floor. The person operating the mop thus has a better control of the mop head at all times, and even after periods of use when ordinarily mop heads become loose, the present mop head maintains its accurate alignment upon the handle.

While in the foregoing specification, I have set out the details of specific structures embodying my invention, it will be understood that such embodiments are illustrative and that those skilled in the art may readily modify such details without departing from the spirit of my invention.

I claim:

1. In a mop structure, a relatively rigid mop head having a central raised portion provided with a longitudinal slot, a handle socket having its forward end received within said socket and having a cam surface inclined downwardly towards said forward end, a pin pivotally connecting said socket within said slot, and a second pin extending through said slotted raised portion forward of said first pin, and a U-shaped spring having central portion wrapped about said second mentioned pin and having a forwardly extending portion engaging said mop head and a rearwardly extending saddle portion resting upon the cam surface of said handle socket.

2. In a shaker mop structure, a relatively rigid mop head provided with a longitudinal slot and having a vertically extending flange about said slot, a handle socket having a tubular handle-receiving portion and a forwardly extending flat portion received within said slot, the upper portion of said forwardly extending portion providing a cam surface inclined downwardly toward said forward end, a pin extending through said flange and pivotally securing the forward end of said handle socket within said slot, and a second pin extending through said flange forward of said first pin, and a U-shaped spring having its central portion wrapped about said second mentioned pin on each side of said slot and having a forwardly extending portion engaging said mop head and a rearwardly extending saddle portion resting upon the cam surface of said handle socket.

FREDERIC E. OAKHILL.
